UNITED STATES PATENT OFFICE

ERNST WECKER, OF HEILBRONN-ON-THE-NECKAR, GERMANY

MANUFACTURE OF ESTERS OF FATTY ACIDS AND OF MIXTURES CONTAINING FATTY ACIDS

No Drawing. Application filed June 20, 1927, Serial No. 200,285, and in Germany June 23, 1926.

This invention relates to a process for the esterification of fatty acids with glycerin or other alcohols.

The esterification of fatty acids is attended with difficulties since, if the whole fatty acid present is to be esterified, the mass action law requires that an excess of glycerin be used and in practice it is scarcely possible to recover the excess of glycerin in a simple manner from the reaction mass.

In contrast therewith the present process provides a very simple and economical method for the esterification of higher fatty acids containing at least 4 atoms of carbon in the molecule, such for example as occur in vegetable and animal fats and oils and the recovery of all the ingredients which have not been esterified, as well as protection for the esterified ingredients. The present process consists in that esterification is carried out without an excess of glycerin, and is only allowed to reach a certain stage, the excess of the fatty acids left in the reaction mixture being removed by a purifying process, in which a suddenly expanding liquid mist is introduced into the heated reaction mixture or by means of neutral gases or superheated vapours which, if desired, may act as carriers for the said liquid mist, the said vapours and gases being equivalents for the purposes of the present invention, which is injurious neither to the fatty acids nor to the neutral oily portions.

The process is therefore carried out so that fatty acids, or neutral oils containing a high percentage of fatty acids, are esterified with an alcohol, preferably glycerin, the quantity of glycerin being so adjusted that it remains below the quantity stoichiometrically required, with the result that while an excess of fatty acid is left all the glycerin present is completely used up in the esterification process.

The resulting reaction mixture containing an excess of fatty acids, is thereupon freed from the said acids in accordance with the process explained above, for example, by heating it to a high temperature, preferably close to the boiling point of the fatty acids, and thereupon treating it with finely divided

liquids such as for example water, toluol, alcohol, etc., which do not injure the fat and which are not confined to solvents for the fatty acids, the said treatment being carried out at low pressure, preferably below 150 mm. of mercury, but better still in a much higher vacuum, for example 10 to 40 mm. of mercury. In place of the finely divided liquid, or in conjunction therewith, superheated vapours or neutral gases, for example hydrogen or the like may be used.

To remove the fatty acids, the reaction mixture to be purified is preferably caused to flow in a relatively thin layer, for example through a washing space subdivided into several single chambers, the conditions being such that the purifying agent remains in contact with the flowing fats or oils for a very short time only, and is then immediately led away with fatty acids and other volatile ingredients.

The excess of fatty acids thus separated may be used afresh in the esterification process.

Thus, according to the present process fatty acids, oils containing fatty acids and mixtures of any origin containing fatty acids, can be esterified in an industrially simple and economical manner. A particularly advantageous feature of the present esterification process consists in that the latter may be used in conjunction with a physical process for refining oils or fats, such as the purifying process hereinbefore described wherein liquid mist, neutral gases or superheated vapours are used. Thus, starting from oils or fats containing more or less fatty acids, the said oils and fats are purified by the said process whereafter the fatty acids or mixtures of fatty acids obtained, which do not contain any, neutral oil, or only relatively small quantities thereof, are submitted to an esterification process together with such quantities of glycerin or other alcohols as are completely used up in the said process. The excess of fatty acids is then removed from the esterification reaction mixture as hereinbefore described, in order that the said excess may again be subjected to the esterification process if desired.

Examples

1. 10 kg. of 93% fatty acid derived from peanuts and about 7% neutral oil are esterified as known with 0.9 kg. of glycerin. At 5 the end of the reaction the reaction mixture still contains 9.5% of free fatty acid. The glycerin is completely consumed, except for traces found in the condenser and which remained therein during several consecutive 10 operations. The acid reaction mixture is treated in a vacuum of 20 mm. at 250° with water mist, the carrier for which is superheated steam. After the rapid separation of the fatty acids 9.38 kg. of neutral oil containing 15 0.4% of free fatty acid remains, while the 0.98 kg. of fatty acids separated are used for a fresh operation.

2. 10 kg. of sesame oil fatty acid with 95% of free fatty acid and about 5% of neutral 20 oil, are esterified with 0.9 kg. of glycerin, as in Example 1. After the reaction is completed, the reaction mixture still contains 11.42% of free fatty acid which was separated (as in Example 1) by superheated 25 steam charged with water mist. The resulting quantity of 9.18 kg. of neutral oil still contains 0.3% of free fatty acid. The 1.18 kg. of fatty acid separated was utilized in a subsequent operation. The glycerin is completely used up.

The new process has the advantage that it can be carried out to afford the greatest possible protection to the existing or newly-formed neutral oils and fats, and that during 35 each stage of the separation of the fatty acids practically colourless and high percentage products are obtained, the renewed esterification of which with glycerin can readily be effected quantitatively. The difficult operation of recovering any glycerin not used up 40 in the reaction, is rendered superfluous and losses of neutral oil are likewise avoided. The utilization of the fatty acids of valuable oils, for example sesame oil, peanut oil, etc., 45 for the manufacture of food is made possible in a simple and economical manner by the present process of esterification.

Wide modifications can be made in the 50 present process either as regards the particular form of the esterification process or the physical washing-out methods used therewith, as well as in respect of the construction of the apparatus used, or the continuous or non-continuous method of treatment and the 55 sequence of the various stages of the treatment, etc.

I claim:

1. A process for the esterification of higher fatty acids containing at least four atoms of 60 carbon in the molecule which consists in treating the said fatty acids with less than the corresponding stoichiometric quantity of alcohols, whereupon the excess of fatty acids is removed by introducing a suddenly expanding liquid mist which is not injurious to 65

any of the components of the reaction into the heated reaction mixture.

2. A process for the esterification of higher fatty acids containing at least four atoms of carbon in the molecule which consists in treating the said fatty acids with less than the corresponding stoichiometric quantity of alcohols, whereupon the excess of fatty acids is removed by introducing a suddenly expanding liquid mist which is not injurious to any of the components of the reaction into the heated reaction mixture under reduced pressure.

3. A process for the esterification of higher fatty acids containing at least four atoms of carbon in the molecule which consists in treating the said fatty acids with less than the corresponding stoichiometric quantity of alcohols, whereupon the excess of fatty acids is removed by introducing a suddenly expanding liquid mist which is not injurious to any of the components of the reaction into the heated reaction mixture at a pressure of less than 40 millimeters of mercury.

4. A process for the esterification of higher fatty acids containing at least four atoms of carbon in the molecule which consists in treating the said fatty acids with less than the corresponding stoichiometric quantity of alcohols, whereupon the excess of fatty acids is removed by introducing a suddenly expanding liquid mist which is not injurious to any of the components of the reaction into the heated reaction mixture in the presence of a neutral gas acting as a carrier for the said mist.

5. A process for the esterification of higher fatty acids containing at least four atoms of carbon in the molecule which consists in treating the said fatty acids with less than the corresponding stoichiometric quantity of alcohols, whereupon the excess of fatty acids is removed by introducing a suddenly expanding liquid mist which is not injurious to any of the components of the reaction into the heated reaction mixture in the presence of a neutral gas acting as carrier for the said mist and under reduced pressure.

6. A process for the esterification of higher fatty acids containing at least four atoms of carbon in the molecule which consists in treating the said fatty acids with less than the corresponding stoichiometric quantity of alcohols, whereupon the excess of fatty acids is removed by introducing a suddenly expanding liquid mist which is not injurious to any of the components of the reaction into the reaction mixture heated close to the boiling point of the fatty acid.

7. A process for the esterification of higher fatty acids containing at least four atoms of carbon in the molecule which consists in treating the said fatty acids with less than the corresponding stoichiometric quantity of glycerin, whereupon the excess of fatty acids

is removed by introducing a suddenly expanding liquid mist which is not injurious to any of the components of the reaction into the heated reaction mixture.

5 8. A process for the esterification of higher fatty acids containing at least four atoms of carbon in the molecule which consists in treating the said fatty acids with less than the corresponding stoichiometric quantity of glycerin, whereupon the excess of fatty acids is removed by introducing water mist into the heated reaction mixture in the presence of superheated steam acting as carrier for the said mist at a pressure of 20 milli-
10 meters of mercury.
